HYDRAULIC PRESS

Relza J. Hess and Frank G. Cizek, Chicago, Ill.,
assignors to American Steel Foundries, Chicago, Ill., a corporation of New Jersey

Application September 13, 1943, Serial No. 502,124

5 Claims. (Cl. 18—16)

1

Our invention relates to presses and more particularly to a hydraulic slugging press for compressing material into a "slug" for manufacturing use.

An object of our invention is to provide a novel mechanism for opening and closing the cover of the forming or material cylinder in which the slug is formed. Our novel mechanism comprehends a link pivoted to the main ram cylinder of the device and to the cover, and a novel cover actuating cylinder device is also pivoted to said link for actuating the same, whereby said cover is urged to open and closed position.

A further object of our invention is to provide link stops on the forming cylinder for adjustable engagement with the link to stop the piston stroke of the cover actuating cylinder device.

Another object of our invention is to provide means for stopping the link with its center line beyond the center line of the connection between the cover and the link in the direction away from the cover actuating cylinder device, whereby no compressive loads are transmitted to said device during formation of the slug within the material cylinder.

Still another object of our invention is to provide means for transmission of loads directly from the cover to the link without transmitting such loads to the pivot means interconnecting the cover and link.

A different object of our invention is the provision of novel hydraulic means for adjusting or controlling the stroke of the main ram or piston and for positioning the same at an initial predetermined point in the material cylinder, thus predetermining the amount of material which may be inserted in said material cylinder preparatory to a slugging operation of the press.

In the drawings, Figure 1 is a side elevation of the upper portion of our novel press illustrating the material cylinder cover and the actuating means associated therewith.

Figure 2 is a front view partially in section and partially in elevation of the structure shown in Figure 1, and Figure 3 is a fragmentary top plan view thereof.

Figure 4 is a side elevation partially in section illustrating the lower end of our novel press including the novel hydraulic means for controlling the stroke of the main press ram.

Describing our invention in detail and referring first to Figures 1 to 3 inclusive, our novel press comprises a frame member generally designated 2 and having intermediate its upper and

2

lower extremities a support web 4 adapted to support the press upon a foundation fragmentarily indicated at 6 (Figure 2). At opposite sides thereof the frame member 2 is provided with spaced jaws or brackets 8 and 10 affording pivotal connection by means of pins 12 and 14 respectively with spaced arms 16 and 18 of the cover link generally designated 20, said cover link including a crosspiece 22 extending between the arms 16 and 18 and pivoted thereto adjacent the upper extremities thereof by means of trunnions 25, 25. The crosspiece 22 comprises a projecting lug or arm 23 pivotally connected at 24 with the piston rod 26 of the cover actuating cylinder device generally designated 28, said device being pivotally mounted at 30 (Figure 1) from a bracket 32 formed or welded on the frame member 2.

A forming or material cylinder 34 is secured to the member 2 by means of tension rods or bolts 36, 36 in shouldered engagement at 38 and 40 with the cylinder 34 and the frame member 2, respectively; and a cover 42 is pivoted at 44 to the cylinder 34. It will be understood that shims may be utilized at 38, 38 to adjust the height of the forming cylinder thus creating any desired initial tension between the forming cylinder and the cover 42 as the latter is urged to closed position.

The cover 42 is pivotally connected by means of a pin 46 to a lug 48 on the crosspiece 22 of the link 20, said lug having a semi-cylindrical surface in thrust engagement at 50 (Figure 2) with a complementary bushing or shoe 51 secured in the top of the cover 42. It will be understood that the connection of the pin 46 to the lug 48 is sufficiently loose, so that thrust loads are transmitted from the cover 42 directly to the lug 48 as at 50 during operation of the press as hereinafter described. This feature is believed to be of considerable significance inasmuch as the loads built up against the cover 42 during operation of the press are of such magnitude that they could not be transferred to the link by means of the pin 46 without increasing the size thereof to an impractical extent.

The expansion stroke of the device 28 is stopped by means of adjustable link stops or bolts 52, 52 mounted on the material cylinder 34 for engagement at 54, as best seen in Figure 1, with the link arms 16 and 18. The bolts 52, 52 are threaded through lugs 56, 56 formed on the material cylinder 34, and these bolts are preferably adjusted by means of their threaded connections so that they will engage the arms 16 and 18 when the longitudinal center line X (Figure 1) of the link

is slightly beyond the vertical center line **Y** through the connection at **46**, in a direction away from the cylinder device **28**.

It will be clearly understood by those skilled in the art that by means of this arrangement loads on the cover **42** during operation of the press are transmitted to the link **20** in such manner that the latter is rotated about its pivot means **12** and **14** in a direction away from the cover actuating device **28**. Thus the crosspiece **22** tends to rotate in a counter-clockwise direction (Figure 1) about its trunnions **25**, **25**, whereby the device **28** is placed under tension but is not subjected to compressive forces during operation of the press.

The distance between **X** and **Y** as illustrated also affords a slight amount of lost motion as the cylinder device withdraws the cover to open position, and it will be understood that this lost motion is of considerable significance in facilitating this movement of the cover to open position.

Integrally formed within the member **2** is a main ram cylinder **58**, within which the main ram or piston **60** is reciprocal by means of hydraulic fluid, such as oil, supplied to the cylinder **58** through ports (not shown). The head **62** of the ram **60** is thus reciprocated within the liner **64**, secured in any convenient manner within the material cylinder **34**, to compress into a slug therewithin the associated material which is inserted into the top of the material cylinder **34** as hereinafter described.

Our invention comprises novel hydraulic means for adjustably controlling the stroke of the ram **60**. To achieve this control, an auxiliary cylinder **66** (Figure 4) is mounted by spaced bolts **68**, **68** on the lower end or head **72** of the main ram cylinder **58**, and an auxiliary ram **70** is reciprocal within the auxiliary cylinder **66**, the upper end of said ram **70** extending through the head **72** of the main ram cylinder **58** for engagement at **74** with the lower end of the main ram **60**. Pressure fluid, such as oil, is supplied to the auxiliary cylinder **66** by means of a supply pipe **76** equipped with a suitable shut-off valve **78**.

It may be noted that suitable packing means **80** is provided to prevent escape of actuating fluid from the upper end of the main cylinder **58**, and, likewise, suitable packing means **82** is provided to prevent escape of the actuating fluid from the lower end of the main cylinder **58**. Suitable packing means **84** is also provided to prevent escape of actuating fluid from the upper end of the auxiliary cylinder **66**.

In operating our novel press, the cover **42** and the link **20** are withdrawn to open position by means of the cylinder device **28** as illustrated in dot and dash lines in Figure 1. Fluid is then admitted to the auxiliary cylinder **66** through the valve **78** and the pipe **76** until the main ram **60** is moved upwardly by the auxiliary ram **70** to a predetermined initial position within the material cylinder **34**, thus predetermining the amount of material which may be inserted or poured into the top of the material cylinder. The lowest initial position of the main ram **60** is illustrated in solid lines in Figure 2, and the highest possible initial position is illustrated in dot and dash lines in said figure.

When the main ram **60** has assumed the desired position within the press cylinder **34**, the valve **78** is closed. The material to be compressed is then inserted or poured into the top of the material cylinder **34**, and thereafter, by means

of the cylinder device **28**, the cover is urged to closed position as illustrated in solid lines in Figures 1 to 3, with the link arms **16** and **18** engaging the stops **52**, **52**. Pressure fluid is then admitted to the main ram cylinder to urge the main ram upwardly, thus compressing the material within the material cylinder **34**.

As will be apparent, any suitable means may be provided, if desired, to evacuate air from the forming or material cylinder, prior to the compressing operation; however such means is no part of the present invention and is therefore not illustrated.

It will be understood, as above described, that during this compressing operation, loads built up against the cover **42** are transmitted to the lug **48** of the crosspiece **22** of the link **20**, and from the arms **16** and **18** of said link to the stops **52**, **52**, and to the pivot pins **12** and **14**, no compressive loads being transmitted to the piston rod **26**. After the material within the material cylinder **34** has been compressed to the desired compactness, the main ram **60** is moved downwardly by means of actuating fluid in the main ram cylinder **58** to release the pressure against the slug and the cover **42**, and thereafter the cover is opened and the slug is ejected from the upper end of the press cylinder by the ram **60**. The main ram **60** is then urged to its lowest and predetermined position against the upper end of the auxiliary ram **70**, and the press is ready for another cycle.

Pressure on the main ram **60** as it is urged to closed position never exceeds the pressure on the auxiliary ram **70**, as will be readily understood.

It is to be understood that we do not wish to be limited by the exact embodiment of the device shown which is merely by way of illustration and not limitation as various and other forms of the device will, of course, be apparent to those skilled in the art without departing from the spirit of the invention or the scope of the claims.

We claim:

1. In a press, a press frame, a material cylinder supported by said frame, a ram, means for reciprocating said ram within said cylinder, a link having spaced arms at opposite sides of said cylinder, means pivoting said arms to fixed portions of said frame, a cover pivoted to said cylinder for opening and closing the same, pivotal connection between a portion of said link and said cover, a power cylinder device operatively connected at opposite ends thereof to said link and to a fixed portion of said frame, and stop means on said frame for engagement with said arms, the longitudinal center line of said link, when said arms are engaged with said stop means, being disposed beyond the center line of the connection between said link and said cover in the direction away from said device, complementary abutting semi-cylindrical thrust transmitting surfaces on said link and said cover, the pivotal connection between said link and said cover being sufficiently loose so that loads on said cover are transmitted therefrom to said link along said surfaces.

2. In a press, a frame, a material cylinder open at both ends thereof and supported by said frame, a cover for closing one end of said cylinder, means reciprocated within said cylinder for compressing associated material therewithin, and actuating means for said cover comprising a link pivotally connected thereto and to said frame, said link and said cover having abutting thrust surfaces, the pivotal connection between said

cover and said link being sufficiently loose to permit the transmission of forces from said cover to said link by means of said surfaces.

3. In a press, a frame, a material cylinder open at both ends thereof and supported by said frame, a cover for closing one end of said cylinder, a pivot pin pivotally connecting said cover to said cylinder, a ram reciprocal within the opposite end of said cylinder, actuating means for said cover comprising a link pivoted thereto and connected to said frame, and means for transmitting forces directly from said cover to said link independently of said pin, comprising complementary arcuate abutting surfaces on said cover and said link.

4. A press of the class described comprising a frame, a material cylinder supported thereby, means for compressing material within said cylinder, a cover member hinged to said cylinder and adapted to close the same, a toggle mechanism comprising pivotally interconnected link members, one of said link members having a pivotal connection to the cover member, and the other of said link members having a pivotal connection to said frame, a power cylinder device supported by said frame and directly connected to one of said members for urging said cover member to the closed position thereof, said cover member and mechanism being so constructed and arranged that in the closed position of said cover member, said other member is disposed a substantial distance beyond the dead center of said mechanism in the direction away from said device, and an abutment intermediate said pivotal connections fixed to said frame and engageable with said other member in the closed position of said cover for transmitting forces on said other member to said frame independently of said device when said cover member is in the closed position thereof.

5. A press of the class described comprising a frame, a material cylinder supported thereby, a cover hinged to said cylinder for closing one end

thereof, means for compressing associated material within said cylinder against said cover when the latter is in its closed position, a toggle mechanism comprising pivotally interconnected links, one of said links having a pivotal connection to said cover and the other of said links having a pivotal connection to said frame, a power cylinder device operatively connected to said mechanism for opening and closing said cover, said cover and said mechanism being so constructed and arranged that in the locked position of said mechanism whereat said cover is in the closed position thereof, said mechanism is beyond the dead center thereof in the direction away from said device, and an abutment surface on said frame independent of said pivotal connections and engageable with said mechanism in the locked position thereof whereby compressive forces on said cover during compression of said material thereagainst are transmitted through said mechanism to said surface thereby substantially eliminating transmission of such forces to said device.
